UNITED STATES PATENT OFFICE.

WILLIAM T. BEATTY, OF FLOSSMOOR, FRANK S. DAVIS, OF HOMEWOOD, AND FRED D. WILSON, OF HARVEY, ILLINOIS, ASSIGNEES TO AUSTIN MANUFACTURING CO., OF CHICAGO, ILLINOIS, A CORPORATION OF ILLINOIS.

TELESCOPING-AXLE, LEANING-WHEEL ROAD GRADER.

Application filed June 7, 1923. Serial No. 643,841.

This invention relates to the well known type of leaning wheel road machines in which for reasons well understood in the art, the rear axle is, in actual operative use at least, very much longer than the normal width of the machine. Such machines of the prior art are objectionable in that the long axle of fixed length constantly extends out into the roadway and interferes with passing traffic, both on and off of bridges which are sometimes too narrow to take the machine with its extended axle at all. As much of the work done by a road machine does not require a long axle at all, it is a valuable feature and an object of this invention to selectively close up and shorten the rear axle when length is no longer required, and to extend it only when required for special work, this while at the same time, under all conditions of use, constantly having the benefit of the leaning wheels on opposite ends of the axle, simultaneously inclinable at the will of the operator by the use of a single mechanism, and this without interfering with bodily shifting the axle across the central axis of the machine should such movement be required.

The invention consists broadly in mechanism attaining the foregoing and other objects and, more particularly, in details of an axle compact in form, easily and cheaply constructable and not readily liable to get out of order, containing or carrying all the mechanism for both extending and contracting the axle and for inclining the road wheels attached thereto. The invention further consists in features and details hereafter more fully set forth in the specification and claims.

Referring to the drawings in which like numerals designate the same parts throughout the several views:

Figure 1 is a side elevation and Figure 2 is a plan view of a machine illustrating this invention in its preferred form.

Figure 3 is a changed position view of the rear axle and wheels from that shown at the right hand end of Figure 2.

Figure 4 is a rear view of the machine taken from the right of Figure 2.

Figure 5 is a modified construction corresponding to Figure 3, showing the axle housing rigidly mounted on the frame of the machine.

Figure 6 is a side elevation of certain parts in section on the irregular line 6-6 of Figure 3.

Figure 7 is a plan view of certain parts in section on the irregular line 7-7 of Figure 6.

Figure 8 is a side elevation on the line 8-8 of Figure 3.

Figure 9 is a sectional end view taken on the irregular line 9-9 of Figure 7.

Figure 10 is a sectional, detailed end view on the line 10-10 of Figure 6.

Figure 11 is a front elevation, largely in section, on the irregular line 11-11 of Figure 2.

Figure 12 is a plan view on the irregular line 12-12 of Figure 11.

Figures 13 and 14 are changed position views of the mechanism of Figures 6 and 7, respectively, showing the wheels moved to extreme extended position.

The drawings show the conventional form of road machine frame 16 with its working tools: specifically, a scraper 18, controllable through a lever mechanism 20-21-22 manipulable by a hand wheel 24 within reach of an operator riding at the rear of the machine.

At the forward end of the frame 16 is a conventional form of fifth wheel mechanism 26 carrying a front axle box 28 rotatable about the axis of a vertical shaft 30, rockable in conventional manner by an operator at hand wheel 32, through the agency of a shaft 34, a worm 36 on said shaft, and a worm wheel 38 on shaft 30.

On the lower end of shaft 30, inside casing 28, is a bevel pinion 40 meshing with a bevel gear 42 on a shaft 44 at right angles to shaft 30. At opposite ends of shaft 44 are bevel pinions 46 and 48. Pivoted on a horizontal axis 50, at the end of shaft 44 which is adjacent to bevel gear 46, is a lever, one of whose ends is a segmental gear 52 meshing with pinion 46, as shown in Figure 12, while its other end is the axle 54 for front wheel 56. Correspondingly mounted on a horizontal axis 58, at the opposite end of shaft 44, is another lever including segmental gear 60, meshing with gear 48, and axle 62 for the opposite front wheel 64. The wheels and the lever mechanisms mounting them are identical in construction except that the segmental gears 52 and 60 are, as clearly shown in Fig-

100
105

ure 12, placed on opposite sides of a vertical plane through the central axis of shaft 44, with the result that as shaft 44 rotates in a given direction, the front wheels 56 and 64 are rocked in the same angular direction at the will of the operator. In other words, if wheel 56 is moved from the full line to the dotted line position of Figure 11, wheel 64 will necessarily be correspondingly removed 10 from its full line to its dotted line position. By the use of the mechanism shown, the operator at wheel 32 can, therefore, straighten up or incline the front wheels of the machine as he may desire.

15 The main body of frame 16 is conventionally arched, as shown in Figure 1, but, in the preferred form of construction, shown in all the figures except Figure 5, terminates at its rear end in a horizontally disposed U-shaped member 66 rigidly secured to the main part of the frame by any suitable means, as for instance hollow triangular members 68 and suitable bolts or rivets 70. The rear or base end of U-shaped member 20 66 is supported upon a rectangular axle box or case 72, reciprocable crosswise of the machine in engagement with this frame. Journalled at each forward end of U-shaped frame 66 in a suitable vertical bearing 74 25 is a horizontally extending lever arm 76 or 78, as the case may be, having adjacent to axle case 72 a vertically extending crank pin 80, journalled in a bearing 82 formed on the adjacent end of case 72. Pivoted on the upper 30 end of each of these crank pins 80 and above the bearing 82 is a bearing 84 slightly longer than the thickness of frame 66 and having at its upper end a horizontally disposed arm 86 so positioned as to support a horizontally 35 disposed cross bar 88 engaging the upper surface of the rear or base member of frame 66, as clearly shown in Figure 10. The result of the construction just described is that as axle case 72 reciprocates across the 40 machine on contact with the lower side of frame 66, the bar 88 correspondingly travels along the upper surface of frame 66 and the case 72 being positioned horizontally by the rods 76 and 78, the parts named can only 45 make the desired reciprocatory motion with reference to frame 66 across the main central axis of the machine. The bearings 84 are so placed on the axle case 72 that they never interfere with or strike the frame 66 50 during the predetermined reciprocation of case 72 across the frame.

Inside the axle case 72, slidably bearing on its vertical side walls are two spaced apart plates 90, secured at their ends which are normally outside the case 70, viz: the right hand end, Fig. 7, to a U-shaped casting 92. In the base of this casting 92, having a bearing 94, is rotatably mounted a horizontal shaft 96, having a squared end 98 extending 55 into the case 72 and a beveled pinion 100.

Telescoping inside case 72 and in immediate contact with plates 90, just referred to, are two other parallel plates 102 secured at their left hand ends (Fig. 7) to a U-shaped casting 104 identical with casting 92. This casting 104 has a bearing 106 for a shaft 108, having at one end a pinion 110 and at the other end a square shaft 112 in alignment and register with shaft 98 so that when the rear wheels of the machine are drawn into their most contracted positions, the adjacent ends of these two square shafts practically abut each other, as shown in Figures 6 and 7. Encasing the two shafts 98 and 112, just described, is a tube 114 carrying at its opposite ends non-circular wrench socket portions 116 and 118, slidably interfitting with the non-circular shafts 98 and 112, respectively, so that when the parts shown in Figures 6 and 7 assume the positions of Figures 13 and 14, and in all intermediate positions, the shafts 98 and 112 will be in driving relation, one with the other, through the agency of this tube 114.

Non-circular shaft end 112 is non-rotatable with reference to a worm gear 120, suitably mounted in bearings 122, rigid with reference to case 72, and this worm gear is selectively rotatable at the will of the operator by any suitable means, as for instance a suitably disposed, intermeshing worm 124, driven by manually operated crank 126 of conventional form. The result of the construction just described is that when the operator rotates crank 126, he thereby rotates worm wheel 120 to thereby rotate telescopic shafts 98-114-112 in all positions assumed by the parts between that of Figures 6 and 7 and that of Figures 13 and 14.

Parallel plates 90 are held in rigid spaced relation by cross-bars 128 and 130, the latter of which carries an upwardly extending stop 132, embracing tube 114 and adapted, when the parts are in the position of Figure 13, to strike a depending stop 134 on the inside of the top wall of case 72 and thus prevent the further outward or right hand movement of the shaft 98.

In similar manner, parallel plates 102 are rigidly separated by horizontally disposed cross-members, one of which 136 carries a depending lug 138 embracing the upper side of tube 114 and is adapted in the position of Figure 13 to engage the stationary bearing 122, heretofore referred to, and thus prevent further movement to the left of squared shaft 112 out of case 72.

At the extreme outer or left hand end of casting 104 and parallel plates 102 is a horizontally disposed, transverse shaft 140, pivotally supporting a lever carrying at one end left hand rear wheel 142 of the machine, and at the other end, a segmental gear 144, meshing with pinion 110. Similarly mounted at the right hand end of parallel plates 130

90 and casting 92 is a horizontally disposed shaft 146, pivotally supporting a lever carrying at its outer end the right hand rear wheel 148 of the machine and at its other end a segmental gear 150 meshing with pinion 100. The gear segments 144 and 150 engage their respective pinions 110 and 100 on opposite sides of a plane through the central axis of a telescoping shaft, with the result that rotation of crank 126 in a given direction will incline both wheels 142 and 148 in the same direction, for instance as shown in Figure 4.

Rigidly attached to transverse shaft 140 and through it to the plates 102 is a horizontally disposed rack 152 extending along the outside of case 72, slidably supported in guides 154 and 156 provided at opposite ends of the case for that purpose. Similarly supported in said guides, in the particular case here illustrated, below rack 152 and in sliding engagement therewith is another rack 158, rigidly connected at its right hand end, as shown in the drawings, to shaft 146 and, consequently, parallel plates 90.

Racks 152 and 158 are held by the guides 154 and 156 a sufficient distance away from case 72 so that they can be enclosed by gear box 160 containing pinion 162, meshing with rack 152, and a laterally disposed pinion 164 meshing with rack 158. The pinions 162 and 164 have non-circular, central openings 166 adapted to be selectively entered by the non-circular lower portion 168 of a vertical wrench shaft 170, manually manipulatable through the agency of a conventional hand wheel 172. The pinion 162 is normally automatically locked in nonrotatable position with reference to the case 160 by a suitably pivoted locking lever 174, in the particular case here illustrated, a gravity lever, actuated by a weight 176. In similar manner, the pinion 164 is automatically secured in stationary position by locked lever 178, actuated by a weight 180. Each of these locking levers, just referred to, is provided with a part 182 or 184, as the case may be, which is in the path of travel of the extreme lower end 186 of shaft 170, with the result that when the shaft is positioned as shown in Figure 9, this lower end portion 186 of the shaft swings the adjacent locking lever to the position assumed by lever 174 (Fig. 9) whereby the particular pinion, in the case mentioned 162, is free to be rotated in unison with hand wheel 172.

Operation.

Assuming that the rear wheels are in the contracted position of Figures 3-6-7-8 and the operator desires to move rear wheel 142 to the left toward the position of Figures 13 and 14, he first places shaft 170 in the position shown in Figures 8 and 9 and rotates

hand wheel 172 in the proper direction to cause pinion 162 to move rack 152 and consequently wheel 142 to the left, as viewed in Figures 6-7 and 8. The insertion of shaft 170 to the position referred to has caused member 186 to release latch 174 so that this movement can take place and the movement does take place because gear case 160 is stationary being anchored to frame 66 through link 188. When the movement of rack 152 and attached parts has progressed from a point where stop 188 engages member 122, as shown in Figure 13, further movement of hand wheel 172 will, within the limits of the remainder of rack 152 not previously traversed by pinion 162, cause casing 72 to swing on arms 76 and 78 across the frame 66 to the position shown in Figure 2. When the operator has positioned the parts referred to in the extreme position just described or in any intermediate position, he withdraws shaft 170 from operative relation with pinion 162, whereupon latch 174 automatically locks the pinion and consequently all connected parts referred to in the new position.

When the operator desires to return wheel 142 to the original contracted position, he merely inserts shaft 170, as before, and rotates wheel 172 in the opposite direction.

When the operator wishes to put wheel 148 in the position shown in Figures 13 and 14, he merely places shaft 170 in operative engagement with pinion 164 and properly rotates wheel 172.

In the modified structure of Figure 5, the horizontal supplemental frame 66 is omitted and main frame members 16 are connected directly to the case 72 by any suitable means, as by bolts or rivets 190. In this construction, the case 72 is immovable with reference to the main frame of the machine and, therefore, when the operator applies shaft 170 and rotates wheel 172, as before, he merely moves the particular wheel controlled to or from the end of the case 72, i. e., he cannot move the casing with reference to the main frame of the machine.

In both constructions, the operator manipulates handle 126 to incline the wheels to the vertical, regardless of the extended positions of the wheels. The friction of the worm gear connection 120-124 serves conventionally as a lock holding the wheels in each inclined position to which they are moved.

As clearly shown in Figures 6-7-13-14, tube 114 is held against endwise movement by members 122 and 134.

Having thus described our invention, what we claim as new and desire to secure by Letters Patent is:

1. A road grader comprising, in combination with a frame part, a wheel supporting

member across the frame, wheels at opposite ends of the wheel supporting member, said wheels being mounted for pivotal movement on horizontal axes, means for independently 5 positioning each wheel to and from its end of the supporting member, and a single means selectively simultaneously inclining both said wheels about said horizontal axes in all their positions beyond the ends of the 10 wheel supporting member.

2. In mechanism of the class described, in combination with a frame part, a wheel supporting member, slideable across the frame, wheels at opposite ends of the wheel supporting member, means for independently 15 positioning each wheel to and from its end of the supporting member, and means actuated by the same means which moves a given wheel outward from the wheel supporting member end, operative after said 20 wheel has reached a predetermined, extended point, shifting said wheel supporting member transversely of the machine frame.

3. In mechanism of the class described, in combination with a frame part, a wheel supporting member slideable across the frame, wheels at opposite ends of the wheel supporting member, means for independently 25 positioning each wheel to and from its end of the supporting member, means actuated by the same means which moves a given wheel outward from the wheel supporting member end, operative after said wheel has reached a predetermined, extended point, 30 shifting said wheel supporting member transversely of the machine frame, and a single means selectively simultaneously inclining both said wheels in all their positions beyond the ends of the wheel supporting member.

4. A road grader comprising, in combination with a frame part, a hollow axle case across the frame, wheels at opposite ends of the hollow axle case mounted on a telescoping axle extending through the case, said wheels being adapted for pivotal movement about horizontal axes, means for independently 45 positioning each wheel to and from its end of the axle case, and a single means selectively simultaneously inclining both said wheels about said horizontal axes in all their positions beyond the ends of the hollow axle case.

5. In mechanism of the class described, in combination with a frame part, a hollow axle case slideable across the frame, wheels at opposite ends of the hollow axle case, mounted on a telescoping axle extending through the case, means for independently 55 positioning each wheel to and from its end of the axle case, and means actuated by the same means which moves a given wheel outward from the hollow axle case end, operative after said wheel has reached a predetermined, 60

extended point, shifting said hollow axle case transversely of the machine frame.

6. In mechanism of the class described, in combination with a frame part, a hollow axle case slideable across the frame, wheels at opposite ends of the hollow axle case, mounted on a telescoping axle extending through the case, means for independently positioning each wheel to and from its end of the axle case, means actuated by the same means which moves a given wheel outward from the hollow axle case end, operative after said wheel has reached a predetermined, extended point, shifting said hollow axle case transversely of the machine frame, and a single means selectively simultaneously inclining both said wheels in all their positions beyond the ends of the hollow axle case.

7. In mechanism of the class described, in combination with a stationary member, an axle case slideable with reference thereto, a wheel carrying axle, reciprocable with reference to the case, and means operating on said axle to first move the wheel a given distance from the case and then move the case and wheel with reference to the stationary member.

8. In mechanism of the class described, in combination with a stationary member, an axle case slideable with reference thereto, a wheel carrying axle reciprocable with reference to the case, and means operating on said axle to first move the wheel a given distance from the case and then, on further continuance of the original movement of said operating means, move the case and wheel with reference to the stationary member.

9. In mechanism of the class described, in combination with a stationary member, an axle case slideable with reference thereto, a wheel carrying axle reciprocable with reference to the case, means moving said axle longitudinally of the case, a stop on the case, and a member moving in unison with the axle engaging said stop in such manner that after said wheel has moved a given distance from the case, further movement of the axle moves the case and extended wheel with reference to the stationary member.

10. In mechanism of the class described, in combination with a machine frame end, an axle case across said frame end, parallel links attached to separated points on the case and to the frame, means on the case embracing two opposite sides of the frame end whereby as the links are rocked, they move the axle across the frame, an axle reciprocable along said case and means anchored to the frame operating on the axle capable of being actuated to first move the axle out of the case a predetermined distance and thereafter shift the case and axle across the frame.

11. In mechanism of the class described,

in combination with a machine frame end, an axle case across said frame end, parallel links attached to separated points on the case and to the frame, means on the case 5 embracing two opposite sides of the frame end whereby as the links are rocked, they move the axle across the frame, an axle reciprocable along said case, means anchored to the frame operating on the axle capable 10 of being actuated to first move the axle out of the case a predetermined distance and thereafter shift the case and axle across the frame, and an automatic lock, normally fastening said actuatable means in each position 15 the parts assume.

12. In mechanism of the class described, in combination with a machine frame end, an axle case across said frame end, parallel links attached to separated points on the case and to the frame, means on the case 20 embracing two opposite sides of the frame end whereby as the links are rocked, they move the axle across the frame, an axle reciprocable along said case, means anchored 25 to the frame operating on the axle capable of being actuated to first move the axle out of the case a predetermined distance and thereafter shift the case and axle across the frame, an automatic lock, normally fastening 30 said actuatable means in each position the parts assume, and an operating tool engageable with said actuatable means, to operate it, acting when so applied to release said lock.

35 13. In mechanism of the class described, in combination with a stationary member, an axle case slideable with reference thereto, a wheel carrying axle, reciprocable with reference to the case, means operating on said 40 axle to first move the wheel a given distance from the case and then move the case and wheel with reference to the stationary member, and an automatic lock, normally fastening said operating means in each position 45 the parts assume.

14. In mechanism of the class described, in combination with a stationary member, an axle case slideable with reference thereto, a wheel carrying axle, reciprocable with 50 reference to the case, means operating on said axle to first move the wheel a given distance from the case and then move the case and wheel with reference to the stationary member, and an operating tool engageable with said operating means, to operate it, acting when so applied to release 55 said lock.

60 15. In mechanism of the class described, a tubular case, a member telescoping with said case carrying a wheel at one end of the case, another member carrying a wheel at the opposite end of the case telescoping on said first wheel carrying member, fixed members rigid with the case stopping movement 65 of said respective telescoping members out

of the case, means independently reciprocating said telescoping members in the case, a telescoping shaft inside the case, one means for rotating said shaft in all positions of the telescoping members, and means so operatively connecting each end of said shaft to the adjacent wheel that rotation of said shaft simultaneously inclines said wheels in the same angular direction. 70

16. In mechanism of the class described, a tubular case; a member telescoping with said case carrying a wheel at one end of the case, another member carrying a wheel at the opposite end of the case telescoping on said first wheel carrying member, fixed members 75 rigid with the case stopping movement of said respective telescoping members out of the case, means independently reciprocating said telescoping members in the case, a telescoping shaft inside the case, one means for rotating said shaft in all positions of the telescoping members, and means at each end of the case, pivotally mounted on the adjacent telescoping member, carrying the adjacent wheel and so operatively connected to the adjacent end of said shaft that rotation 80 of said shaft simultaneously inclines said wheels in the same angular direction. 85

17. In mechanism of the class described, a tubular case, a member telescoping with 90 said case carrying a wheel at one end of the case, another member carrying a wheel at the opposite end of the case telescoping on said first wheel carrying member, fixed members rigid with the case stopping movement 95 of said respective telescoping members out of the case, means independently reciprocating said telescoping members in the case, means normally automatically locking each reciprocating means in whatever position it 100 is placed by the operator, a telescoping shaft inside the case, one means for rotating said shaft in all positions of the telescoping members, and means so operatively connecting each end of said shaft to the adjacent wheel 105 that rotation of said shaft simultaneously inclines said wheels in the same angular direction. 110

18. In mechanism of the class described, a tubular case, a member telescoping with 115 said case carrying a wheel at one end of the case, another member carrying a wheel at the opposite end of the case telescoping on said first wheel carrying member, fixed members rigid with the case stopping movement 120 of said respective telescoping members out of the case, means independently reciprocating said telescoping members in the case, means normally automatically locking each reciprocating means in whatever position it is placed 125 by the operator, a telescoping shaft inside the case, one means for rotating said shaft in all positions of the telescoping members, and means at each end of the case, pivotally mounted on the adjacent telescoping member, 130

carrying the adjacent wheel and so operatively connected to the adjacent end of said shaft that rotation of said shaft simultaneously inclines said wheels in the same 5 angular direction.

19. In mechanism of the class described, a tubular case, a member telescoping with said case carrying a wheel at one end of the case, another member carrying a wheel at the opposite end of the case telescoping on said first 10 wheel carrying member, fixed members rigid with the case stopping movement of said respective telescoping members out of the case, a pair of racks outside said case, reciprocatable with reference thereto and with reference to each other, one being attached to each of said wheel carrying reciprocal members, a gear case carrying two pinions, one meshing with each rack, means rendering said gear 15 case stationary, means independently operating a selected one of said pinions, means automatically locking the other pinion, a telescoping shaft inside the case, one means for rotating said shaft in all positions of the 20 telescoping members, and means so operatively connecting each end of said shaft to the adjacent wheel that rotation of said shaft simultaneously inclines said wheels in the same 25 angular direction.

20. In mechanism of the class described, a tubular case, a member telescoping with said case carrying a wheel at one end of the case, another member carrying a wheel at the opposite end of the case telescoping on said first 30 wheel carrying member, fixed members rigid with the case stopping movement of said respective telescoping members out of the case, a pair of racks outside said case, reciprocatable with reference to each other, one being attached to each of said wheel carrying reciprocal members, a gear case carrying two pinions one meshing with each rack, means rendering said gear 35 case stationary, means independently operating a selected one of said pinions, means automatically locking the other pinion, a telescoping shaft inside the case, one means for rotating said shaft in all 40 positions of the telescoping members, and means at each end of the case, pivotally mounted on the adjacent telescoping member, carrying the adjacent wheel and so operatively connected to the adjacent end of said shaft that rotation of said shaft simultaneously inclines said wheels in the same 45 angular direction.

21. In mechanism of the class described, in combination, a pair of wheels tiltable in vertical planes about horizontal axes adjustable towards and away from one another, and means constantly connecting said wheels operable to tilt them simultaneously in all positions of adjustment thereof.

22. In mechanism of the class described, a frame, a wheel supporting member movable across said frame, wheels carried by said

member adjustable towards and away from the same, and a single means operable to so adjust said wheels and to move said member across the frame.

23. In mechanism of the class described, in combination, a frame, a member movable with respect to said frame, a wheel support carried by and movable with respect to said member, and means for moving said member with respect to said frame operatively connected to said member by said wheel support. 70

24. In a road grader, an axle, a pair of vertically tiltable wheels therefor, adjustable devices for contracting and extending the axle and means adjustably controlling in unison the vertical angle of said wheels in all positions of the axle, said means being adapted for operation during the adjustment of said adjustable devices. 80

25. A road grader comprising, in combination, a frame, supporting wheels therefor tiltable in vertical planes about horizontal axes, means for independently moving said wheels towards and away from the frame as the grader is in motion, and means connecting said wheels operable to tilt them simultaneously about said axes in all positions of adjustment thereof while the grader is moving over the ground. 85

26. A road grader comprising, in combination with a frame, supporting wheels therefor mounted on horizontal axes, means for independently adjusting said wheels towards and away from the frame, and a single means operable to tilt said wheels simultaneously about said horizontal axes in all positions of adjustment thereof, each of said means being adjustable while the grader is moving over the ground. 90

27. In a machine of the character described, a vehicle frame, a pair of laterally extensible rear axle sections, a wheel mounted on each axle section for shifting movement, manually operable means for adjustably shifting each axle section inward or outward independently of the other axle section, means coacting with each axle section and operatively engaged with the wheel thereof for tilting said wheels, and manually operable means for operating said tilting means 105 mounted independently of the axle sections and fixed with relation to the vehicle frame but having constant engagement with the tilting means of both wheels in all positions of the axle sections. 110

28. In a machine of the character described, a vehicle frame, rear axle sections independently shiftable laterally to extend or retract the axle sections, manually operable means for shifting each of said axle sections independently of the other, a knuckle pivotally mounted upon each axle section, for movement in a vertical plane, a wheel carried by the knuckle, adjusting means mounted upon the axle sections for move- 125 130 135

ment therewith and operatively connected to the corresponding knuckle for simultaneous movement therewith, and manually operable means for tilting the knuckle, said means being fixed with relation to the vehicle frame but having constant engagement with said knuckle.

29. In a machine of the character described, a pair of extensible rear axle sections, guides within which each axle section is longitudinally shiftable transversely of the machine, a knuckle pivotally-carried upon the extremity of the axle section, a wheel mounted upon the knuckle for tilting movement therewith, means for tilting the knuckle and wheel comprising coacting members mounted upon and movable with the corresponding axle section, one of said means being rotatable, means for rotating the rotatable means of both axle sections comprising a shaft extending parallel to the axle section and held from longitudinal movement therewith but coactively connected to one of said coacting members, and manually operable means for rotating said shaft.

30. A road grader comprising, in combination, a frame, a pair of wheels tilttable in

vertical planes about horizontal axes, one at each side of said frame, independently adjustable towards and away from the frame, and means connecting said wheels operable to tilt them simultaneously in all positions of adjustment thereof, said tilting means being automatically extended, or contracted, as either wheel is adjusted away from, or towards, said frame.

31. A road grader comprising, in combination, a frame, a pair of wheels tilttable in vertical planes about horizontal axes at different sides of said frame, respectively, independently adjustable towards and away from the frame, and extensible and contractible means connecting said wheels operable to tilt them simultaneously in all positions of adjustment thereof, said tilting means being automatically extended, or contracted, as either wheel is adjusted away from, or towards, said frame.

In witness whereof, we have hereunto subscribed our names.

WILLIAM T. BEATTY.
FRANK S. DAVIS.
